UNITED STATES PATENT OFFICE.

EDWARD W. LEECH, JR., OF BALTIMORE, MARYLAND.

SAFETY LOCK FOR STOPCOCKS.

Application filed August 10, 1921. Serial No. 491,194.

To all whom it may concern:

Be it known that I, EDWARD W. LEECH, Jr., a citizen of the United States, residing at Baltimore, in the State of Maryland, have 5 invented certain new and useful Improvements in Safety Locks for Stopcocks; and I do hereby declare the following to be a full, clear, and exact description of the invention, such as will enable others skilled in 10 the art to which it appertains to make and use the same.

My invention relates to safety locks for stop cocks.

Among the objects of my invention are:— 15 To produce a safety lock suitable for use with the stop cock of an ordinary gas range, to prevent the inadvertent operation of the stop cock.

To produce a safety lock for stop cocks 20 capable of easy application to the stop cocks of an ordinary gas range.

To produce a safety lock for stop cocks which can be cheaply manufactured and 25 readily applied by unskilled persons.

25 In carrying out my invention I make use of the instrumentalities illustrated in the accompanying drawings, in which:—

Figure 1 is a section of the manifold of 30 an ordinary gas range showing one stop cock connected thereto and my improved safety lock mounted thereon, the stop cock being in the off position.

Fig. 2 is a view of the parts shown in Fig. 1 looking in the direction of the arrow 2 35 in said figure.

Fig. 3 is a view of the parts shown in Fig. 2 looking in the direction of the arrow 3 in said figure.

Fig. 4 is a view of the bracket for holding 40 my improved lock when viewed in the direction of the arrow 3 in Fig. 2.

In the drawings:—

10 represents the ordinary manifold used to convey gas to the burners of a gas range. 45 11 and 12 are, respectively, the body and valve portions of the stop cock, the latter being operated by the handle 13. A spring such as 14 and screw 15 are usually employed to keep the valve 12 seated within the 50 body 11. The body 11 and valve 12 are provided with the usual passages so that when the handle 13 is in the position shown in Figs. 1 and 2 and by full lines in Fig. 3 the egress of gas from the manifold 10 55 through the body 11 to the gas burner is prevented.

The parts thus far described are of any usual or approved construction but as they act in combination with my improved lock they form part of my invention.

16 is a clamp preferably formed of sheet metal which encircles the manifold 10 and has its ends 17—17 brought together and pierced for the reception of the bolts 18—18. The bracket 19 is also pierced by the slot 22 for the reception of said bolts and any suitable number of washers such as 20 may be placed between the top end 17 and the bracket 19. Nuts 21 serve to clamp the ends 17, bracket 19 and washers together.

The upper end of the bracket 19 is slotted as at 23 and provided with holes for the reception of the pivot 24. The bottom of the slot 23 is cut to form the oblique face 25 shown in Fig. 1 and the lower end of the lock 26 is cut to fit against said face when the lock 26 is in the position shown in Fig. 1, thereby preventing said lock from moving below said position.

The lock 26 is curved to embrace the 30 handle 13 and is provided with a finger grip 27 for the application of the fingers thereto and for the purpose hereinafter explained.

The lock 26 is loosely mounted upon the pivot 24 and is normally kept by gravity in 35 the position shown by full lines in Fig. 1.

The operation of my improved lock is as follows:—

The forefinger being applied to the end 28 of the handle 13, the thumb is applied to 40 the finger grip 27 and the lock 26 is moved to the position shown dotted in Fig. 1. The handle 13 can then be moved from the position shown by full lines in Fig. 3 to the position shown dotted in said figure. When 45 the thumb is removed from the finger grip 27 the force of gravity returns the lock 26 from the position shown dotted in Fig. 1 to the position shown by full lines in said figure.

When the handle 13 is moved from the position shown dotted in Fig. 3 to the position shown by full lines in said figure, the body of the handle 13 presses against the curved portion 29 of the finger grip 27 and moves the lock 26 from the position shown by full lines in Fig. 1 towards the position shown by dotted lines in said figure until the handle 13 passes under the point 30 of the lock 26 when said lock drops to the position 50 shown by full lines in Fig. 1.

By loosening the nuts 21 the bracket 19

(see Fig. 1) may be slid either toward the right or toward the left in order to make the lock 26 function properly with the handle 13.

5. For the same purpose by the use of more or less of the washers 20 the bracket 19 may be moved upwardly or downwardly.

Thus it will be seen that I provide a simple, cheap and effective lock for preventing the inadvertent operation of stop cocks, in which many changes may be made without departing from the spirit of my invention.

I claim:—

15. 1. The combination with a manifold, a stop cock connected therewith and a handle for operating said cock, of a clamp on said manifold, a bracket supported by said clamp, and a lock pivotally mounted on said bracket and engaging said handle to stop

motion of said handle in one direction, said bracket projecting into the path of said handle to stop motion of said handle in the other direction.

2. The combination with a manifold, a 25 stop cock connected therewith and a handle for operating said cock, of a clamp on said manifold, a bracket supported by said clamp, and a lock pivotally mounted on said bracket and engaging said handle to stop motion of said handle in one direction, said bracket projecting into the path of said handle to stop motion of said handle in the other direction and being adjustable with 30 reference to said clamp in order to vary 35 the stopped position of said handle.

In testimony whereof, I affix my signature.

EDWARD W. LEECH, JR.
